(No Model.)

T. H. WHITE.

FIRE PROOF COMPOSITE ROOF.

No. 313,971.

Patented Mar. 17, 1885.

Fig. 1.

UNITED STATES PATENT OFFICE.

THOMAS H. WHITE, OF ST. LOUIS, MISSOURI.

FIRE-PROOF COMPOSITE ROOF.

SPECIFICATION forming part of Letters Patent No. 313,971, dated March 17, 1885.

Application filed January 12, 1885. (No model.)

To all whom it may concern:

Be it known that I, THOMAS H. WHITE, of St. Louis, Missouri, have invented certain new and useful Improvements in Fire-Proof Composite Roofs, of which the following is a full, clear, and exact description, having reference to the accompanying drawings, forming part of this specification.

This invention relates to a water and fire proof composite roof, the several parts of which are so laid and secured that not only can the work be done with facility, but also so as to fasten the slates that form the superimposed or protective layer in a manner that they are secure from any danger of creeping or sliding on or from their bed. It also is designed to obviate the difficulty that has long been experienced in concrete, bituminous, and other forms of composite roofs arising from the alternate expansion and contraction of the material of which the bed-layers are composed, (from change of temperature,) which thereby moves the superimposed or wearing layer and the parts or sections of which it is composed, which, especially in sloping or pitch roofs, are not apt to return to their previous positions. So, also, in another class of superimposed layers for concrete or composite roofs, in which the wearing-surface is composed of gravel concreted with asphalt, bitumen, pitch, &c., it is a well-known fact that in consequence of expansion and contraction the gravel by these often-recurring reactionary forces becomes loosened from the bituminous or other adhesive ingredients, and also in the act of displacement and separation breaks off portions of the cement that once held it in position, and so the waste continues, and each recurring shower washes loosened material into the eavestroughing, preventing the free passage of the water. Also, in many cases where (in hopes of overcoming the latter difficulty) slate, tile, brick, &c., have been used as an auxiliary layer or taken the place of the concrete from the alternating causes above noted, they have soon commenced to sag and tilt, and thus present an uneven surface to the weather, retarding the escape of the water from the roof instead of facilitating its passage. To obviate

these various difficulties and to secure a roof 50 that shall continue intact alike under the influence of heat and frost, is the intention of this invention.

My invention consists in the use of copper or other metallic band or wire clamps that, 55 passing through prepared slots and holes in adjoining slates or other equivalent material constituting the superimposed or wearing layer of a composite roof, securely holds the same with a smooth and even surface to the weather, 60 whatever may be the expansion or contraction from change of temperature in the bed-layers beneath.

My invention also consists in laying the slate or its equivalent in a shallow bed-layer of 65 warm plastic pitch or other bituminous material, thus avoiding the necessity of heating the slate to enable it to embed itself in the layer beneath. It is a well-known fact that slate when heated to a high temperature loses its 70 integrity, and soon scales and breaks.

Referring to the drawings, Figure 1 is a detail top view showing the different layers or sections of the roof and the method of securing the slates of my composite roof. Fig. 2 is a 75 cross-section on line 2 2, Fig. 1. Fig. 3 is a diagram showing the method of securing the slates in position. Fig. 4 is a section taken on line 4 4, Fig. 3; and Fig. 5 is a detail transverse section at the peak or ridge of the roof, 80 showing the ridge straps or clamps and their attachment to secure the opposite sides of the roof in counterpoise.

A represents the sheathing-boards that support the roof, which are preferably not jointed, 85 thus providing an opportunity for the felt, with its bituminous interlayers, to key itself between the interstices of adjoining boards, thus forming a rigid connection with the sheathing-boards below.

B represents two or more layers of roofing felt or paper, cemented together with tar, pitch, or other suitable bituminous material. The roofing-felt is so placed as to break joints in its layers.

C designates the bed-layer, of pitch or other bituminous material, on which the superimposed layer of slates D are placed and embed-

ded while the bed is warm and plastic. By this method the necessity of heating the slate, so as to enable it to bed itself, and the consequent loss of integrity in the slate itself, is 5 avoided.

E and E' are slotted apertures and holes in adjoining slates, in which the band-clamps F and wire clamps F' engage and secure the slates in position with a smooth and even wearing-surface and presentation to wind and weather. It will be seen that by this novel method of fastening the slates the permanence of a level lay is secured, as it is impossible for any of them to get out of position; so, also, for 10 the same reason, a very thin bed-layer alone is needed beneath them, which, also, is a great advantage, for, in the first place, the thin bed has not so great a power of expansion and contraction to strain the superimposed layer of 15 slate above it; and, secondly, there is a great saving of material and consequent advantage in reduction of weight. This last is an advantage readily appreciated by those skilled in the art to which this invention pertains, who 20 have a knowledge of the strong supports required to sustain a heavy concrete or composite roof.

G is a cant-strip at the eaves, rising just flush with the surface of the bituminous or 25 bed layer, keeping it from overflowing its bounds in the course of construction and from waste afterward. The cant-strip also supports the weight of the overhanging slates at the eaves, so that however much the bituminous 30 cement may be softened by heat the slates cannot unduly press thereon. The cant-strip also forms a ready means of attachment for the eaves-troughing, into which the slates empty.

H are staples that, passing through holes 35 H' in adjoining slates at the eaves, fasten into the cant-strip G, and serve the double purpose of holding the slates down to their place at the eaves, and supporting the roof from a tendency to creep or slide, especially when 40 its bed-layer is softened by heat.

I represents metallic strap-clamps, for use 45 in double-pitch roofs. These clamps are somewhat similar but heavier than those that connect the individual slates. They pass 50 through and engage in slotted apertures I' in the upper tier or ridge slates connecting the corresponding sides of the roof and holding them in counterpoise with each other.

The aforesaid strap-clamp I and staples H 55 are of especial use when the invention is ap-

plied to sloping and double-pitch roofs. Nails may also be used as additional security for attaching at the ridge of pitch-roofs.

The slotted and other apertures, as also the heads of the clamps, &c., are covered smoothly over with asbestos cement, or its equivalent. 60

This invention, unlike most other composite roofs, is alike suitable for application to both flat and pitch roofs. It is also, from its 65 lightness and peculiar attachment of the slates, especially adapted for a renewal roof, it being of easy and secure application to cover and entirely hide the shingle and other old roofs.

I claim as my invention—

1. In a composite roof, the method herein described of connecting the adjoining edges of the slates D by clamps that engage in apertures formed in the slates forming the superimposed layer of a composite roof, substantially as and for the purpose set forth. 70

2. In a composite roof, the combination of the sheathing-boards A, two or more layers of roofing felt or paper, B, dressed with tar or other suitable bituminous material, pitch, or 80 bituminous bed-layer C, with the slotted slates and clamps by which they are attached, all substantially as described, and for the purpose set forth.

3. In a composite roof, the combination of 85 slates secured by clamps, cant-strip G, and staples H, passing through the slates into the cant-strip, all substantially as described, and for the purpose set forth.

4. In a composite roof, the combination of 90 the sheathing-boards, roofing felt or paper, pitch, or other bituminous bed-layer, and superimposed layer of slate, and attaching clamps and staples, substantially as and for the purpose set forth.

5. In a composite roof, the combination of 95 the slates secured by clamps, and the straps or clamps I, extending over the peak or ridge of the roof, substantially as described, and for the purpose set forth.

6. A composite roof composed of the sheathing-boards, roofing-felt, bituminous bed-layer, cant-strip, perforate slates, clamps, staples, and asbestos-cement, all combined substantially as described, and for the purpose set 100 forth.

THOMAS H. WHITE.
